DYNAMIC CONTROL BY INTERTUBE
COUPLING DEVICES

John Hays Hammond, Jr., Gloucester, Mass., assignor to Hammond Holding Corporation, Gloucester, Mass., a corporation of Delaware

Application February 15, 1933, Serial No. 656,813

14 Claims. (Cl. 179—100.1)

The invention relates to amplifying systems used for reproducing music or speech from sound records and more particularly to means for controlling the gain ratio of such amplifying systems.

According to the invention, the gain ratio of a multi-stage vacuum tube amplifier is controlled by varying the impedance of the coupling between stages. This does not change the operating points of the tubes. This impedance may include another vacuum tube which will be called, for purposes of description, a coupling tube. The impedance of this tube may be controlled by the potential of its grid which, in turn, may be controlled by the dynamics of the sound fed to the amplifier.

The control of the gain ratio may be such as to amplify the louder notes more in proportion than the softer notes. This is often desirable in reproducing sound from a sound record or talking film where normally the contrast between loud and soft notes is not sufficiently emphasized for perfect reproduction. Or, the gain ratio control may be arranged to have just the opposite effect, that is, to amplify the softer notes more in proportion than the louder notes. If desired, a reversing switch may be provided so that the amplifier be changed from one type of operation to the other immediately.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 illustrates diagrammatically a circuit according to the invention;

Figs. 2 to 4, inclusive, illustrate modified circuits having different types of variable impedance intertube coupling devices; and

Fig. 5 illustrates diagrammatically the operation of the circuit shown in Fig. 1.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific dis-

closure of the invention is made for purposes of explanation, but it will be understood that the details may be modified in various respects without departure from the broad aspect of the invention.

Referring now to the drawings, and more particularly to Fig. 1, the system as shown comprises the amplifier tubes 22, 24, 27 and push pull amplifier 44 of a multi-stage vacuum tube amplifier. Tube 25 constitutes the coupling tube for varying the impedance of the coupling between tubes 24 and 27.

Sound energy is supplied to the amplifier tube 22 from a sound record which may be either on a moving film or on a rigid wax record.

In the drawings, light from a source 10 is focused by a lens 11 through an aperture 12 in the aperture plate 3 upon the sound track of a moving film 14. The light which passes through the film 14 is focused by means of a lens 114 upon a photoelectric cell 15 which changes the light variations into electrical variations. These variations pass through transformer 16 to the double-pole double-throw switch 17.

For receiving sound from a disk or other wax record (not shown) a pick-up 18 is provided which is also connected to a double-pole double-throw switch 17. By operating switch 17 sound from either type of record may be reproduced.

The switch 17 is connected to a transformer 21 which is connected in the input circuit of amplifier tube 22. The output circuit of tube 22 is connected to the input circuit of amplifier tube 24 through a transformer 23.

Connected to the output circuit of amplifier tube 24 is a choke coil 31. In parallel therewith is the coupling tube 25. The choke coil 31 and coupling tube 25 are connected to the input of the next amplifier tube 27 through a blocking condenser 26.

It will be noted that the plate circuit of coupling tube 25 and the choke coil 31 are in parallel and that variations in the impedance of the plate circuit of coupling tube 25 will vary the gain ratio of the amplifier.

In addition, variations in the impedance of the coupling tube 25 is accompanied by variation in the direct current through the tube, which also must pass through choke 31, and alter its reactance in a well known manner. Since decreased impedance of the coupling tube is accompanied by larger current flow, it is evident the tube impedance and choke reactance vary in the same sense, and are additive in their effects upon

change of coupling impedance in the plate circuit of the tube 24.

For controlling the impedance of coupling tube 25 a control tube 28 is provided whose input circuit is connected to the input circuit of amplifier tube 24. The output of control tube 28 is fed through transformer 29 to a rectifier circuit, including rectifier 35. Connected in circuit with the rectifier 35 through a 3-pole double throw 10 reversing switch 36 is a biasing resistance 37 across which is connected a condenser 38.

C batteries 41 and 42 are connected to the reversing switch 36 and to the biasing resistance 37 so that the bias on the grid of the coupling 15 tube 25 is determined by the battery bias, and the variable bias due to rectified current through resistor 37. C battery 34 gives the proper bias to the amplifier tube 27 through resistance 35. The A battery for supplying cathode heating current 20 to the several tubes is denoted by 32 and the B battery for supplying plate current to the tubes 27, 24, 25 and 28 is denoted by 33.

The output of the amplifier tube 27 is then fed through transformer 43 to a push pull amplifier 44 which in turn feeds a loud speaker 46 through a transformer 45. The stationary coil of the loud speaker is denoted by 47 and is energized by a source of direct current, indicated by 48.

30 In the operation of the circuit shown in Fig. 1, the switch 17 is thrown either up or down, according to whether it is desired to receive a selection from the moving film 14 or the pick-up 18. In either case the sound energy is amplified by 35 the tube 22 and then impressed upon the next stage 24. The energy is further amplified by tube 24 and is impressed by means of the coupling devices 31 and 25 upon the next stage 27 where the energy is further amplified and fed 40 to the push pull amplifier 44 which in turn feeds the loud speaker 46 in a manner which will be apparent to those skilled in the art.

The gain ratio of the multi-stage amplifier is controlled by varying the impedance of coupling tube 25. This is done by the energy which is amplified by the control tube 28 and which is rectified by the rectifier 35 and which passes through the biasing resistance 37 in a direction depending upon the position of switch 36.

50 When the switch 36 is in its upper position the multi-stage amplifier acts as a volume expander. In other words, it so affects the dynamics of the sound impressed upon the amplifier that it amplifies the loud notes more in proportion than the 55 soft tones. When the switch 36 is in its lower position the multi-stage amplifier operates as a volume compressor and amplifies the loud notes less in proportion than the soft notes.

When the switch 36 is in the upper position the 60 current from the rectifier passes through the biasing resistance in the direction of the upper arrow 51. The C battery 41 is in series with the resistance 37 and assists the latter in impressing a negative bias upon the grid of coupling tube 65 25. The louder the sound the more current will flow through the biasing resistance 37 and the greater will become the negative bias on the coupling tube. This raises the impedance of the coupling tube 25 which increases the voltage 70 impressed upon the next stage tube 27, which increases the amplification of the louder notes more than the soft notes.

When the switch 36 is thrown to its lower position the current through the biasing resistance 27 75 flows in the direction of the lower arrow 52 and

both C batteries 41 and 42 are connected so as to oppose the resistance drop in resistance 37. Together, batteries 41 and 42 and resistance 37 control the bias upon the grid of the coupling tube 25.

In this case, the louder the sound, the greater will be the flow of current through the resistance 37. This will result in a decrease in the bias on the grid of coupling tube 25. This decreases the impedance of coupling tube 25 which increases the flow of plate current there through and decreases the potential impressed upon the next amplifier stage tube 27, resulting in a decrease in amplification with an increase in sound energy, and vice versa.

Fig. 5 illustrates diagrammatically the operation of the circuit shown in Fig. 1. In this figure the impressed signal is represented by the alternating current source 123 and the internal impedance of the electron discharge device 24 is represented by the resistance 124. The choke coil 31 15 20 is represented by the variable inductance 131 and the electron discharge device 25 by the variable resistance 125.

The system shown in Fig. 1, the operation of which is diagrammatically shown in Fig. 5, varies 25 from other similar systems in that the impedance of the device 24, as represented by the resistance 124, remains substantially constant and the entire control is exercised by varying the coupling devices, represented by the variable inductance 20 131 and the variable resistance 125, between the stage 24 and the subsequent stage 27.

If desired, the choke coil 31 may be replaced by a non-inductive resistance, making the circuit resistance-coupled instead of inductance-coupled. 25 The operation of this modified form will be obvious from the description above.

Referring to Fig. 2, it will be seen that in place of an inductance coupling between amplifier tubes 24 and 27 a transformer 61 is provided. The 40 coupling tube 25 is connected across the primary of the transformer 61 and operates to control the potential across the next stage tube 27 in a manner similar to that described above.

Referring now to Fig. 3, the amplifier tubes 24 45 and 27 are transformer coupled and a variable impedance made up of resistance 62 and coupling tube 25 in series is connected across the output of transformer 61. The choke coil 63 is connected in the plate circuit of coupling tube 25 to feed 50 it with plate current from B battery 33.

In this case the control circuit is analogous to a potentiometer, whereby lowering of the impedance of the tube 25 cuts down the amount of voltage transfer from secondary winding of transformer 61 to the grid of the tube 27.

Referring now to Fig. 4, amplifier tubes 24 and 27 are shown as coupled together by an inductance 66. The iron core of this inductance is also wound with a winding 68 which receives rectified current from the rectifier 35, this current flowing in a direction depending upon the position of switch 65. Condenser 67 is provided to smooth out the current flow through the winding 68.

When the switch 65 is in its upper position, the current flow through the winding 68 is in the same direction as the current through other winding of the choke coil 66 due to the B battery 33. Any increase in sound strength causes an 70 increase in the current flowing through the coil 68. This will further saturate the iron core of choke coil 66, decreasing its permeability and decreasing the reaction of the choke coil 66 to the output of the amplifier tube 24. This will cause 75

a greater sound current to flow through the choke coil 66 which will decrease the voltage impressed upon the next amplifier tube 21, which in turn will decrease the gain ratio of the multi-stage 5 amplifier.

When the switch 65 is in its lower position, the current through the winding 68 is reversed. In this case, increase in signal strength causes an increase in the permeability of the iron core of 10 choke coil 66 which increases the reactance of this choke coil. This decreases the amount of sound current flowing through the choke coil, which increases the voltage across the next stage 21, which causes an increase in the gain ratio 15 of the multi-stage amplifier.

It may be noted that the operation of Fig. 4 differs from that of Fig. 1 by emphasizing the change of reactance component of coupling impedance, whereas Fig. 1 emphasizes primarily 20 changes of resistance component of the coupling impedance, with the reactance change an incidental effect.

Thus it will be seen that a multi-stage amplifying system has been provided in which the gain 25 ratio is controlled by the impedance of the inter-stage coupling devices. The impedance is controlled by the dynamics of the sound impressed upon the amplifier either to compress the volume ratio or expand it.

30 While certain novel features of the invention have been disclosed and are pointed out in the annexed claims, it will be understood that various omissions, substitutions and changes may be made by those skilled in the art without departing from the spirit of the invention.

What is claimed is:

1. In a system for use with a phonograph record, a multi-stage amplifier, a coupling device between stages of said amplifier, means for 40 changing the volume ratio of the sound by varying the said coupling device, and a change over device for changing from volume expansion to volume compression.

2. In an amplifying system for use with a sound record, an amplifier comprising a first amplifier tube and a second amplifier tube, a variable impedance coupling said tubes, a control tube fed by the sound energy, a rectifier for rectifying the output of said control tube, means for varying 45 said impedance comprising a control circuit fed by said rectifier to vary the gain ratio of the amplifier, and means for reversing the direction of the control current through said control circuit to either expand or compress the volume ratio.

55 3. In a phonographic system, a sound record, a translating device associated therewith, a multi-stage amplifier connected to said translating device, a second translating device connected to said amplifier, a transformer coupling between stages of said amplifier, a variable impedance tube having its plate connected across the primary of said transformer coupling and means controlled according to the dynamics of the sound for varying the impedance of said impedance tube.

4. In a phonographic system, a sound record, a translating device associated therewith, a multi-stage amplifier connected to said translating device, a second translating device connected to said amplifier, a transformer coupling between adjoining stages of said amplifier, a resistance across the secondary of said transformer coupling, said resistance comprising a fixed resistance and the 75 plate circuit of a control vacuum tube in series

therewith, and means controlled according to the dynamics of the sound for varying the impedance of said tube.

5 5. In a phonographic system, a sound record, a translating device associated therewith, a multi-stage amplifier connected to said device, a second translating device connected to said amplifier, an impedance coupling between adjoining stages of said amplifier, said impedance coupling having an iron core and a secondary winding and means 10 controlled according to the dynamics of the sound for controlling the saturation current through said secondary winding.

15 6. In a phonograph system, a first translating device, a second translating device, a circuit between said devices, a coupling impedance in said circuit, and control means for varying the value of said impedance, said control means being governed by a moving average of the energy fed to said circuit by the first translating device. 20

25 7. In a phonograph system, a first translating device, a second translating device, a circuit between said devices, a coupling impedance shunt across said circuit, and control means for varying the impedance value of said shunt, said control means being governed by a moving average of the energy fed to said circuit by the first translating device. 25

30 8. In a phonograph system, a first translating device, a second translating device, a circuit between said devices, a coupling transformer in said circuit, a resistance shunt across the primary of said transformer, and control means for varying the value of said resistance shunt, said control means being governed by a moving average of 35 the energy fed to said circuit by the first translating device.

35 9. In a phonograph system, a first translating device, a second translating device, a circuit between said devices, a transformer in said circuit, 40 a resistance shunt across the secondary of said transformer, and control means for varying the resistance of said shunt, said control means being governed by a moving average of the energy fed to said circuit by the first translating device. 45

45 10. In a phonograph system, a first translating device, a second translating device, a circuit between said devices, an inductance shunt across said circuit, said shunt comprising a winding having a core of magnetic material and means 50 for varying the saturation of said core, said means being governed by the moving average of the energy fed to said circuit by the first translating device.

55 11. In a phonograph system, a first translating device, a second translating device, a circuit between said devices, an impedance in said circuit and control means for varying the value of said impedance, said control means being governed by a moving average of the energy fed to 60 said circuit by the first translating device, the action of said control means being reversible.

65 12. The method of transferring sound to or from a sound record which comprises varying the gain of a multi-stage vacuum tube amplifier by automatically varying the tightness of the coupling device between stages according to a sub-audio control current representing the moving average of the rectified audio frequency.

70 13. The method of reproducing sound from a sound record and expanding the dynamics of the sound which comprises translating the sound variations on the record into corresponding electrical variations, amplifying said electrical variations, passing said electrical variations through 75

a variable coupling device, then further amplifying said electrical variations, translating the electrical variations as thus amplified into compressional sound waves, rectifying a portion of the 5 electrical variations, and controlling the tightness of said coupling devices by said rectified electrical variations.

14. In a sound reproducing system, a sound record, a pick-up device therefor, a multi-stage 10 amplifier fed by said pick-up device, a speaker fed by said amplifier, said amplifier including at

least two vacuum tube stages having coupling devices between stages, a control channel fed by said pick-up device for controlling the gain of said amplifier, said control channel comprising a rectifier for producing a sub-audio control current, and means for causing said sub-audio control current to vary the tightness of a coupling device according to the moving average of the sound energy to expand the volume range of the audible signal.

JOHN HAYS HAMMOND, JR.
